US00D813952S

(12) **United States Design Patent** (10) **Patent No.:** **US D813,952 S**
(45) **Date of Patent:** **** Mar. 27, 2018**

(54) **CONVERTIBLE TIERED GAME SYSTEM**

(71) Applicant: **Scott Siepmann**, Scottsdale, AZ (US)

(72) Inventor: **Scott Siepmann**, Scottsdale, AZ (US)

(**) Term: **15 Years**

(21) Appl. No.: **29/573,511**

(22) Filed: **Aug. 5, 2016**

Related U.S. Application Data

(63) Continuation-in-part of application No. 29/563,589, filed on May 5, 2016, which is a continuation-in-part

(57) **CLAIM**

The ornamental design for a convertible tiered game system, as shown and described.

DESCRIPTION

FIG. 1 is a perspective view of an embodiment of an ornamental design for a convertible tiered game system; FIG. 2 is a front elevational view of the convertible tiered game system, the back, right, and left elevational views being identical in shape and appearance;

FIG. 3 is a top view of the convertible tiered game system; FIG. 4 is a bottom view of the convertible tiered game system;

FIG. 5 is an exploded view of the convertible tiered game system components that are configured to rest on a tiered base of the convertible tiered game system;

FIG. 6 is a perspective view of a first alternative embodiment of the tiered convertible tiered game system;

FIG. 7 is a front elevational view of the first alternative embodiment of the convertible tiered game system, the back, right, and left elevational views being identical in shape and appearance;

FIG. 8 is a top view of the first alternative embodiment of the convertible tiered game system;

FIG. 9 is a bottom view of the first alternative embodiment of the convertible tiered game system; and,

FIG. 10 is an exploded view of the first alternative embodiment of the convertible tiered game system components that are configured to rest on a tiered base of the first alternative embodiment of the convertible tiered game system.

Broken lines and unshaded portions contained within broken lines depict unclaimed portions of the tiered beverage pong game system.

1 Claim, 10 Drawing Sheets

Related U.S. Application Data

of application No. 15/147,840, filed on May 5, 2016,
now Pat. No. 9,808,689.
